US00D835712S

(12) United States Design Patent (10) Patent No.: US D835,712 S
Peterson (45) Date of Patent: * Dec. 11, 2018

(54) TYPEFACE

(71) Applicant: Darren E. Peterson, Danville, CA (US)
(72) Inventor: Darren E. Peterson, Danville, CA (US)
() Term: 15 Years
(21) Appl. No.: 29/573,615
(22) Filed: Aug. 8, 2016
(51) LOC (11) Cl. 18-03
(52) U.S. Cl.
USPC D18/28
(58) Field of Classification Search
USPC D18/24, 26, 27, 28, 29, 30, 31, 32, 33
CPC B41B 1/02
See application file for complete search history.
